Primary Examiner — George D Kirschbaum*Assistant Examiner* — Jennifer Watkins(74) *Attorney, Agent, or Firm* — Luedeka Neely Group, P.C.(57) **CLAIM**

The ornamental design for a portable dry bag soft cooler, as shown and described.

DESCRIPTION

FIG. 1 is a perspective view of a front left side of the portable dry bag soft cooler with the cooler lid closed; FIG. 2 is a front view of the cooler;

FIG. 3 is a view of shoulder straps, a waistband and the back side of the cooler;

FIG. 4 is a view of the left side of the cooler;

FIG. 5 is a view of the right side of the cooler;

FIG. 6 is a top view of the cooler; and,

FIG. 7 is a bottom view of the cooler.

The broken lines illustrate stitching and form a part of the claim.
